US0D1077155S

(12) **United States Design Patent** (10) **Patent No.:** **US D1,077,155 S**
(45) **Date of Patent:** **** May 27, 2025**

(54) **FOLDING TOILET**

- (71) Applicant: **Miaow Intelligent Technology (Shanghai) Co., Ltd.**, Shanghai (CN)
- (72) Inventor: **Xuguang Dai**, Shanghai (CN)
- (73) Assignee: **Miaow Intelligent Technology (Shanghai) Co., Ltd.**, Shanghai (CN)

(**) Term: **15 Years**

(21) Appl. No.: **29/978,534**

(22) Filed: **Dec. 13, 2024**

Related U.S. Application Data

- (63) Continuation-in-part of application No. 29/930,826, filed on Mar. 4, 2024, now Pat. No. Des. 1,059,558.

(57) **CLAIM**

The ornamental design for a folding toilet as shown and described.

DESCRIPTION

FIG. 1 is a front, left and top perspective view of a folding toilet, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the folding toilet in a first usable state.

FIG. 10 is another front, left and top perspective view of the folding toilet in a second usable state.

FIG. 11 is another front, left and top perspective view of the folding toilet in a third usable state; and,

FIG. 12 is another front, left and top perspective view of the folding toilet in a fourth usable state.

The dashed broken lines depict portions of the folding toilet that form no part of the claimed design.

1 Claim, 12 Drawing Sheets
